UNITED STATES PATENT OFFICE.

JOHN F. TEEHAN, OF BROCKTON, MASSACHUSETTS.

ARCH-SUPPORTING SHOE.

1,144,740.

Specification of Letters Patent. Patented June 29, 1915.

Application filed August 15, 1914. Serial No. 856,955.

To all whom it may concern:

Be it known that I, JOHN F. TEEHAN, a citizen of the United States, and a resident of Brockton, in the county of Plymouth and

5 State of Massachusetts, have invented certain new and useful Improvements in Arch-Supporting Shoes, of which the following is a specification.

This invention has relation to arch supporting shoes for preventing or relieving flat foot of the general character of that illustrated in my co-pending application Serial No. 727,584, filed October 24, 1912.

The present invention has for its object 15 to provide certain improvements therein such as improved means for securing the free end of the arch support to the upper, to provide for stiffening the inner side of the shoe and for securing ventilation of the 20 shoe.

Other improvements are pointed out at length in the following specification, illustrated upon the drawings, and pointed out in the appended claims.

25 Referring to the drawings,—Figure 1 represents in side elevation a shoe embodying one form of my invention. Fig. 2 represents a horizontal section therethrough. Fig. 3 represents a longitudinal section 30 therethrough. Fig. 4 represents a transverse vertical section. Fig. 5 represents a longitudinal section similar to Fig. 3 but with the arch support removed. Fig. 6 illustrates the formation of the inner side 35 of the upper during the process of construction of a shoe. Fig. 7 represents a section on the line 7—7 of Fig. 6. Fig. 8 illustrates the next step in the formation of the upper and the attachment of the wires to receive 40 the hooks of the arch support. Fig. 9 represents a section on the line 9—9 of Fig. 8. Fig. 10, illustrates a side elevation of the arch supporting member to illustrate the 45 hooks thereon. Fig. 11 illustrates a section on the line 11—11 of Fig. 10. Fig. 12 illustrates an enlarged section on the line 12—12 of Fig. 5. Fig. 13 represents an enlarged section on the line 13—13 of Fig. 5.

The result which I desire to achieve by 50 my invention is the raising or supporting of the foot below the arch in much the same manner as it would be supported by a bandage attached to the outer side of the foot and then passed under the arch to a point at 55 the outer side of the ankle, so that the foot

will be rocked laterally outwardly and the arch supported above the inner sole of the shoe. To this end, the arch support consists of a flexible band the outer lower edge of which is secured at the junction of the outer edge of the innersole and the upper, and the inner and upper end of which is attached to the side of the upper at a point relatively remote from the inner edge of the innersole.

60 On the drawings, the arch support consists of a band 20, which in width is about equal to one-half of the length of the shoe. It is preferably formed of material such as split sole leather, and its ends are skived. The inner and outer end of this band is 65 permanently secured to the interior of the shoe at the junction of the upper and the innersole. As shown in Fig. 4, the outer and lower end of the band is inserted between 70 the outer edge of the innersole and the upper and the vamp of the upper, and is secured in place by stitches 21 which attach together the innersole 22, the vamp 23 and the welt 24. From this point, the band 75 crosses the interior of the shoe above the innersole, and its inner and upper end is secured to the upper by adjustable fastenings comprising hooks and bars adapted to be engaged thereby.

80 In order that the inner and upper end of the band or arch support may be adequately supported, I preferably employ a counter 250, which, at the inner side of the shoe, is extended forwardly to a point as far as the 85 front edge of the arch support, as shown in Fig. 2, or at a point opposite the ball of the foot. The band itself lies across the shoe above the shank thereof, being sufficiently wide (lengthwise of the shoe) to support 90 the arch from a point near the ball of the foot to a point near the heel. The inner quarter 25 of the upper, as shown in Fig. 6, is formed or provided with a depending flap 26 which has a plurality of elongated 95 apertures 27. This tab 26 depends below the upper edge of the counter at the inner side of the shoe. The lining 28 of the quarter is likewise perforated or apertured as indicated in Fig. 7. Placed outside of the tab 100 26 and covering the same are one or more layers 29 of leather or canvas, the edges of which are secured by stitches 30. Between the tab or flap 26 and the outer covering 29 therefor are arranged parallel wires 31 in- 110

serted in sockets formed by rows of stitches 32. These wires are visible through the apertures 27, as shown in Fig. 5, and they are located between the tab or flap 26 on one side and the covering 29 and the counter on the other side. The vamp 23 and the quarter 25 are secured together by one or more rows of stitches 320 as usual, this row of stitches being above the base of the tab or flap 26, so that the latter is supported in part by the stiffness of the counter.

It will be observed from Fig. 5 that the wires, which are supported by the quarter, are above the inner side edge of the inner-sole, said wires serving detachably to receive one or more hooks affixed to the inner and upper end of the arch supporting band 20. These hooks are indicated at 33 and they are affixed near the extremity of the band on the outer side thereof, being secured in place by any suitable means as by eyelets or grommets 34. As shown in Fig. 13, the hooks 33 may be passed into the apertures 27 so as to engage any one of the wires 31 and thus hold the inner upper end of the band in position to maintain the body of the band at a distance from the inner edge of the inner-sole, see Figs. 4 and 13. Thus a space is left between the arch support and the innersole. The arch support is preferably perforated as indicated at 36.

To provide for the ventilation of the shoe, eyelets 37 are passed through the inner side of the shoe near the upper edge of the counter, the inner ends of these eyelets being covered by the inner upper end of the band. These eyelets provide ports through which the air may pass into and out of the space in the shoe between the arch support and the innersole.

It is quite evident, from the description which I have given, that the shoe may be made either by the welt process or may constitute what is termed a McKay shoe. Furthermore, it may be either a laced shoe or a button shoe. In any event, when the shoe is laced or buttoned and the quarters are drawn tightly about the upper part of the foot, and about the ankle if it be a high shoe, the strain upon the arch supporting band will be borne in part by the stiff counter and in part by that portion of the upper which is on the outer side of the foot. The band is thus held at its ends with its middle portion free, said middle portion being elevated above the innersole as described. The distance to which the middle portion of the band is raised may be varied by engaging the hooks 33 with a higher or lower wire 31.

It will be apparent that the details of construction which I have thus specifically described may be varied to suit the particular style of shoe being made and the requirements of the wearer.

Having thus explained the nature of my said invention and described a way of making and using the same, although without attempting to set forth all of the forms in which it may be made or all of the modes of its use, what I claim is:

1. A shoe having an upper, and innersole, an arch support secured at the junction of the upper and the outer side of the inner-sole, a bar supported by the upper above the inner side of the innersole, and hooking means on the free end of the arch support for engagement with said bar to elevate the arch support above the innersole.

2. A shoe having a counter extending longitudinally of the shoe at the inner side thereof and terminating near the waist of the shoe, fastening members attached to the upper adjacent the upper edge of the counter extension, and an arch support consisting of a band attached at its lower and outer end at the junction of the upper and the outer side of the innersole and having on its upper and inner end fastening members for engagement with the first-mentioned fastening members, said parts being so connected and arranged that the counter assists in sustaining the upper end of the band.

3. A shoe having on its inner quarter a depending tab or flap, and a vamp attached to the quarter by the usual line of stitches above the tab or flap, a counter lying between the tab or flap and the vamp immediately below the stitches, and an arch support crossing the innersole from the outer edge thereof and having one end attached to said tab or flap.

4. A shoe having on the interior of the inner side of the upper a series of bars longitudinal of the shoe and elevated above the innersole, and an arch support crossing the inner face of the innersole and having on its inner end hooking means for engaging said bars to elevate the body of the arch support above the innersole.

5. A shoe having on the inner side of the upper a series of parallel bars longitudinal of the shoe, and an arch support crossing the inner face of the innersole with its outer end attached to the outer edge of the innersole and having on its inner end hooking means to engage said parallel bars.

6. A shoe having its inner quarter and the corresponding portion of the lining formed with an aperture, an outer cover for said aperture, a bar between the cover and the quarter and crossing the aperture, and an arch support within the shoe having means for engagement with said bar.

7. A shoe having an arch support crossing above the shank of the innersole, with its outer end attached to the outer edge of the innersole and its inner end attached to the upper above the inner edge of the innersole to leave a space between the support and

the innersole, and ventilating passages through the inner side of the upper leading from said space.

8. A shoe having an arch support crossing above the shank of the innersole, with its outer end attached to the outer edge of the innersole and its inner end attached to the upper above the inner edge of the innersole to leave a space between the support and the innersole, and a counter having an extension on the inner side of the shoe to give
- 5
- stiffness to that part of the upper immediately beneath the point of attachment of the inner end of the arch support to assist in sustaining the inner end of the arch support. 15

In testimony whereof I have affixed my signature, in presence of two witnesses.

JOHN F. TEEHAN.
